MULTICONTACT PLUG

Karl J. Braun, Ridgewood, N. Y., assignor to
Remington Rand Inc., Buffalo, N. Y., a corporation of Delaware

Application May 20, 1937, Serial No. 143,646

3 Claims. (Cl. 173—328)

This invention relates to multi-contact plugs, and particularly to the method of constructing and assembling them.

Previous to the present invention multi-contact plugs were used in connection with Powers punches, as is shown in Fig. 1 of the copending application Serial No. 635,186. These plugs, however, were very cumbersome and inconvenient to use, and were very expensive to manufacture. They required quite some adjusting and were very heavy. The best plugs which were previously available had many disadvantages, in that they were constructed of a series of stepped insulating tubes, which tubes were nested one within the other. Spaced about the surfaces of these insulating tubes were a number of contact fingers which were very heavy. Each contact finger was fastened to its tube by two countersunk screws, and the fingers had to be made so heavy that only a limited number could be screwed to each tube. Hence, while the fingers on any one tube were identical, they were different in length than the fingers on any other tube, so that several different kinds of fingers were necessary. All the insulating tubes were held together by an insulating pin, and it was very difficult to disassemble one of these plugs when a contact needed replacing. Due to the heaviness of the assembly, it was necessary to screw one part of the plug to the punch-frame, whereas the present plug permits of a driving fit.

The present invention is a multi-contact plug which is very light and which provides wiping contacts throughout. Its shell is made, generally speaking, in two parts. Each part contains a pair of insulating discs which may be moulded to receive contact fingers. The contact fingers in the present invention are all alike, and may be made of very light material, and they are formed with centrally located shoulders. These shoulders fit into the insulating rings which lock the fingers in place, and keep the contact fingers from moving after assembly. A pair of spring pressed latches, pivoted on the outside of one part of the shell, coact with a pair of shouldered screws on the other part of the shell to hold the plug together when it is in use.

One object of the present invention is to provide a multi-contact plug which is light and durable.

Another object is to produce a plug in which the contact fingers are all identical.

A third object is to produce a plug which is easily disassembled.

56 Another object is to produce a multi-contact

plug in which the contact fingers are easily and quickly removable, so as to facilitate replacement.

Other objects and structural details of the invention will be apparent from the following description when read in connection with the accompanying drawings in which:

Fig. 1 is an elevation of the plug showing it completely assembled, but with some of the contact fingers left out for the sake of clearness;

Fig. 2 is a vertical cross-section taken along the line 2—2 of Fig. 1, and showing the two parts of the plug spaced slightly apart;

Fig. 3 is a vertical cross section of the outer shell showing the three parts spaced slightly from one another;

Fig. 4 is an elevational detail view of the insulating assemblies in the plug, and showing the positions of opposing contact fingers in relation to each other;

Fig. 5 is a front elevational detail of one of the contact fingers;

Fig. 6 is a side elevation of one of the contact fingers;

Fig. 7 is a detail elevation of the male center contact piece;

Fig. 8 is an isometric view of one of the shell latches;

Fig. 9 is a complete assembly elevational view of one set of contacts;

Fig. 10 is a top plan view of one of the contact finger retaining discs.

As will be seen from Figs. 1, 2, and 3, the plug has an outer casing or shell which, in the present embodiment, is made in three pieces 1, 2, and 3 respectively. This outer casing is made of any suitable strong material such as steel, etc., so that it can withstand jarring and other heavy usages. The part 3 is made with a shoulder 4, and this shoulder 4 is driven tightly into a frame wall 5 of any machine upon which the plug is to be mounted. The shell piece 3 is also cut with a groove 6 to receive the lower part of the piece 2. A pin 7 protrudes inwardly from the groove 6, and cooperates with a slot 8 on the shell piece 2 so as to keep the tube 2 from turning when it is in engagement with the piece 3, and to enforce proper alignment of the contacts in bringing pieces 2 and 3 together. The top piece 1, in the present instance, is formed to give a close driving fit in the piece 2, so that once it is driven in, it will remain due to friction only. It will, however, be seen that the pieces 1 and 2 could be made as a single piece and that, in substance, they are just that.

Fig. 1 shows the plug completely assembled and

mounted as it is in actual use. Here it will be seen that the shell pieces 2 and 3 are locked together by a pair of latches 9, only one of which is shown in this figure. The latches 9 are pivotally mounted by shouldered screws 10 upon opposite sides of the shell piece 3. As is most easily seen from Fig. 8, the latches 9 are formed with hooks 11, and are provided with finger-pieces 12. Returning to Fig. 1, it is seen that the hooks 11 cooperate with shouldered screws 10A to lock the shell pieces 2 and 3 together. Springs 13 tend constantly to press the latches 9 counter-clockwise, as seen in Fig. 1, into locking position. To remove shell piece 2 from shell piece 3, it is only necessary to press the finger-pieces 12 clockwise, and then pull out the shell piece 2.

Referring particularly to Figs. 2, 4 to 7, 9, and 10, it is seen that each of the shell pieces 2 and 3 contains a contact unit which consists of a pair 20 of insulating discs 14, an insulating collar 15, a plurality of contact fingers 16, and a center contact member 17 or 17A, the contact 17 being a male contact, and the contact 17A being a female contact. The members 17 and 17A are threaded 25 at one end and run through the centers of the insulating discs. Nuts 18 hold the assemblies together, so that they may be inserted as units into their respective shell pieces. As is most clearly shown in Fig. 4, the center contact members 17 30 and 17A are formed so that one fits into the other thus giving a wiping contact.

The contact fingers 16 are made of any suitable springy metal which is a good conductor of electricity. In the present instance they are 35 made of beryllium copper. Each contact finger is the same size and shape as any other, and thus it is seen that they may very conveniently be die-stamped at very low cost. Referring particularly to Figs. 5, 6, and 10, it is seen that each finger 16 40 is formed with slight extrusions 19 near its middle, and it will also be seen that the insulating discs 14 are moulded to receive these extrusions. The parts are so formed, that when 45 they are assembled the insulating discs 14 engage the shoulders and hold the fingers 16 firmly in place.

As is seen in Fig. 2, the contact units are held in their respective shell pieces by means of screws. The screws 10 and 10A, previously mentioned, 50 are threaded into two of the discs 14, and short screws 20 and 20A are threaded into the remaining discs. The insulating collars 15 are here used merely to space the inner fingers 16 from the center contacts 17 and 17A.

Should any of the contact fingers 16 become 55 damaged, it is only necessary to remove the contact unit from its shell, remove the nut 18, and pull the discs 14 apart. The damaged fingers can then be removed and new ones inserted.

Due to the fact that bent ends of the contact 60 fingers in one shell piece point inward, while those in the other shell piece point outward, a wiping contact is made every time the shell piece 2 is plugged into the piece 3. As is well known, 65 this type of contact is self cleaning, and is con-

sidered the best type of electrical contact now known for plugs.

While I have described what I consider to be a highly desirable embodiment of my invention, it is obvious that many changes in form could be 5 made without departing from the spirit of my invention, and I, therefore, do not limit myself to the exact form herein shown and described, nor to anything less than the whole of my invention as hereinbefore set forth, and as herein- 10 after claimed.

What I consider new, and desire to secure by Letters Patent, is:

1. A multi-contact plug comprising a pair of shell members, a pair of spring-pressed latches 15 carried by said shell members for latching said shell members together; and a pair of contact units, one for each shell member, secured in said shell members; each contact unit comprising a plurality of identical one-piece springy contact 20 fingers formed with centrally located shoulders, a pair of contact insulating and retaining discs each formed with a plurality of countersunk holes arranged in rings about the center thereof for holding said contact fingers, an insulating collar 25 for preventing short circuiting, and a centrally located contact for securing together the insulating pieces of said contact unit.

2. A contact unit for electrical plugs including a plurality of flat single-piece removable springy contact fingers formed with a pair of centrally located shoulders all of said contact fingers being identical in shape and size, a pair of identical contact insulating and retaining members each formed with a plurality of holes arranged in rings 35 about the center thereof, each hole being formed with a pair of countersunk shoulders for receiving and retaining one of said removable contact fingers, an insulating collar for preventing short circuiting, and a centrally located contact member 40 having a threaded shank and a cooperating nut for locking together the insulating members of said contact unit.

3. A multi-contact plug comprising a pair of shell members, a pair of spring-pressed latches 45 carried by one of said shell members for locking said members together, and a pair of contact units, one secured in each shell member, each contact unit comprising a plurality of flat spring contact fingers having centrally located shoulders formed thereon, a pair of retaining discs of insulating material having a plurality of countersunk holes arranged in rings about the center thereof adapted to hold said contact fingers therein with the ends thereof extending beyond 55 the outer faces of said discs, and a centrally located contact member having a threaded shank and a cooperating nut adapted to secure the members of said unit into an integral structure, said centrally located contact member having a 60 disc of insulating material positioned thereon to prevent short circuit between said central contact and the inner ring of said spring contacts.
